UNITED STATES PATENT OFFICE.

WILLIAM R. BURROWS, OF NEWARK, NEW JERSEY, ASSIGNOR TO GENERAL ELECTRIC COMPANY, A CORPORATION OF NEW YORK.

METHOD OF MAKING LAMP MOUNTS AND SIMILAR ARTICLES.

Application filed November 25, 1921. Serial No. 517,737.

To all whom it may concern:

Be it known that I, WILLIAM R. BURROWS, a citizen of the United States, residing at Newark, county of Essex, State of New Jersey, have invented certain new and useful Improvements in Methods of Making Lamp Mounts and Similar Articles, of which the following is a specification.

My invention relates to the manufacture of incandescent lamp mounts and similar articles comprising two stiff leads or wires embedded in a glass bead and supporting a short wire or filament to which these leads also supply current. This type of mount is used extensively in flashlight lamps designed to operate on low voltage, such as two to four volts. These mounts must be made with great accuracy to insure that the correct length of filament is included in circuit between the leading-in wires, and heretofore it has been necessary to have these mounts made by comparatively skilled labor in order to obtain lamps made accurately enough to be of the desired uniformity in candle power and voltage.

One object of my invention is to provide an improved method of performing those operations of mount making which must be done with great accuracy and which heretofore could be performed successfully only by skilled operators.

Another object of my invention is to provide a method for making such mounts which are more accurately made and more uniform than similar mounts heretofore made by the skilled operators ordinarily available in a lamp factory.

A further object is to provide a simple and efficient method of securing the filament to the leading-in wires with the proper length of filament in circuit between them and shaping the filament with a degree of accuracy and uniformity not usually obtainable under ordinary factory conditions.

Still another object is to provide a method by which a filament of the proper length may be applied to the leads of the mount while it is part of a long filament wire wound on a spool, and then cut off from the spool of wire, in such a manner that mounts may be made rapidly and with a high degree of accuracy and uniformity.

Other objects and advantages of my invention will appear from the description of the particular embodiment of the apparatus

which is described in the following specification and by means of which my method may be practiced, the novel features of my method being pointed out with greater particularity in the annexed claims. My invention is capable of being carried out in many different ways, and various elements of the apparatus illustrated for practicing my method may be changed and modified without departing from my invention.

The accompanying drawings illustrate a desirable form of apparatus for practicing my invention commercially, and in these drawings Figure 1 is a view in perspective of one form of finished mount which may be made by my method; Figs. 2, 3, 4, 5, 6, 7, 8 and 9 are diagrammatic views to illustrate the sequence of operations by which in accordance with my invention the filament is put in place, attached to the lead wires, shaped, and cut off from the spool of filament wire with the end of the wire ready to be secured to a lead wire of the next mount; Fig. 10 is a side elevation of the filament feeding mechanism with a part of the mount carrying table and one of the pinching jaws shown to illustrate the relations of the parts; Fig. 11 is a view in perspective of part of the filament feeding mechanism in its forward position corresponding to Figs. 2 to 5; Fig. 12 is a perspective view of part of the filament feeding mechanism in its retracted position, corresponding to Figs. 8 and 9; Fig. 13 is a plan view, with certain parts broken away, of a preferred form of machine; Fig. 14 is a side view of the indexing or locating pin which accurately positions and firmly holds the rotatable table so that each mount will be in proper relation to the mechanism which operates on it; Fig. 15 is a side view of the spacing and cutting mechanism which spaces the ends of the leading-in wires the proper distance apart and simultaneously cuts them to the proper length, and also positions them at the proper distance from the center of the rotating table; Fig. 16 is a plan view looking down upon the spacing and cutting blades with parts of the blades omitted to show more clearly the relation of the blades to the leading-in wires and the mount holder; Fig. 17 is a plan view of the filament attaching mechanism with the filament wire feeding mechanism omitted for clearness of illustration; Fig. 18 is a side

view of the mechanism shown in Fig. 17; Fig. 19 is a side view of the same mechanism shown in Fig. 17, but with the parts in a different position; Fig. 20 is a diagram illustrating the connections of the cutter for electrically cutting the filament wire, and Fig. 21 is a side view of the cutter showing the swinging arm which brings it into contact with the filament wire.

10 My method of making mounts can be practiced by hand to advantage, but can to greater advantage be carried out by means of machinery, and therefore I have illustrated it in connection with a suitable form 15 of machine. My improved method can better be understood by referring to Fig. 1, showing one form of finished mount which can to advantage be made by my method. This particular form of mount comprises 20 a metal wire or filament 30, usually of drawn tungsten, and reversely curved into an S shape, although the filament may be bent or curved into other shapes, and for some low voltage lamps may be straight. 25 The ends of the filament are secured to the upper ends of the leads 31 and 32, held side by side and at the proper distance apart by a glass button 33 in which the leads are embedded. These leads are rigid enough 30 to act as supports for the filament as well as to carry current to it. I prefer to make each lead of a wire consisting of a core of nickel iron having a coefficient of expansion less than glass and a sheath of copper 35 welded to the core to form a composite wire which as a whole has the right coefficient of expansion to make a hermetical seal with glass. This lead requires no welds or joints, such as are required where the lead is of 40 a metal like copper or nickel and must be welded to a wire which will make a hermetical seal with glass.

In accordance with my novel method of attaching the filament to the leads to obtain 45 with great accuracy the correct exposed length, by which I mean the length of filament in circuit, a long filament wire, usually of drawn tungsten and wound on a spool, is placed with its free end adjacent or adjoining one of the accurately spaced leads, such as the lead 31, as shown in Fig. 3, but with the remainder of the wire at such a distance from the other lead 32 that there is no danger of the other lead being displaced by contact with the wire. The end 50 of the filament wire is firmly held in a definite position with reference to the first lead 31, preferably by being in effect fastened to the lead, as by some kind of clamping or pinching device, and then by movement of the leads, or of the filament wire, or both, the other lead 32 and the filament wire 30 are swung or moved toward each other to place the wire adjacent the other lead 32 and in effect measure off a definite 55

length of filament in such a way that when the wire is attached to the leads a definite and uniform length of filament will be in circuit. If the filament is straight a relative movement of leads and wire which results in the wire being stretched from one lead to the other is sufficient, the exposed length of filament being in that case equal to the spacing of leads. By my method of applying the filament wire the leads are accurately spaced, and as their spacing is not altered, the mounts produced all have substantially the same exposed length of filament.

After the filament wire has been positioned to be in contact with the leads at two points a definite distance apart, the leads are permanently secured to the wire at those points. This may be done in various ways, but I prefer to embed the hard filament wire in the comparatively soft lead and thereby make a good electrical connection that is mechanically strong. This may be done by pressing the wire and lead together with pinchers with sufficient force to cause the wire to sink into and be embedded in the lead. This operation can be performed easily and quickly without moving the lead along the wire and thereby altering the length of wire in circuit, and is therefore a desirable way of fastening the filament to the leads when making a mount in accordance with my method.

In the mounts most generally used the exposed length of filament is greater than the distance between the leads, and therefore the filament is bent or shaped in some manner, usually into a zigzag or S-shape, such as shown in Fig. 1, although it may be given any shape which will permit the necessary length of wire to be included in circuit between the leads. By my method the filament wire is bent or shaped while its end is firmly held adjacent or clamped to one lead such as 31, and while the wire is kept away from the second lead 32, so there is no danger that the bending and shaping of the filament wire will move or displace the second lead 32 and thereby alter the exposed length of filament. At the conclusion of the shaping operation the shaped filament is in place between the leads and the wire is in proper relation to the second lead 32 ready to be secured to it. The filament can be shaped by bending it over any kind of a former or shaper, and brought in proper relation with the second lead by relative movement of the leads and the filament wire. A convenient shape to impart to the filament is the reverse curve or S-shape illustrated in Fig. 1, which can be given to the wire by bending it over a shaper. The shaper may have two shaping members, such as the end of a flat shaping blade 34 placed adjacent the first lead 31 and the end of the wire 30, as indicated

in Fig. 4, and over which the wire may be bent in one direction, and also bent back over a second shaping member such as the end of a second flat blade 35 held adjacent to the first, as indicated in Fig. 7. The wire can be bent back and forth over the shaping members in various ways, but I prefer to clamp the end of the wire to one lead 31 as, for example, by gripping the lead and the wire overlapping it between the shaping blade 34 and a pinching jaw 36 with sufficient pressure to clamp the wire immovably to the lead, and then move the shaper 35 to bring it alongside the first blade and thereby bend the wire and also lay it across the other lead 32, as indicated in Fig. 7. I further prefer to make the shaper or former of such a size that it substantially fills the space between the two leads, and to bring it, with the shaped filament on it, into place between the leads, with the ends of the shaped filament lying across the leads and perpendicular to them, and then by means of the pinching jaw 36 and a cooperating pinching jaw 37 exert sufficient pressure in a direction along the line joining the leads to sink or embed the wire in the leads, as indicated in Fig. 8. To this end the shaping blades 34 and 35 are of such a thickness that when side by side with the wire on them, as shown in Figs. 7 and 8, they hold the leads and wire in such position that the closing of the pinching jaws embeds the wire in the leads.

By making the first bend of the wire around the shaper 34 while the end of the wire is firmly held, and then completing the bending by moving the other shaper 35 into place alongside the first, the work of bending the wire and pulling into place between the leads whatever extra length of wire is needed to make a filament of the proper length is all done by the shapers, without displacing either of the leads 31 or 32. By my method the proper length of wire for a filament is accurately measured off when it is shaped, and can be varied by varying the amount of wire on the shaper, as for example, by varying the amount of overlap of the shaping blades 34 and 35. The filament length is very definite and very uniform, as the shaper blades can be made to overlap to the same extent each time a filament is shaped, and the leads and filament of all mounts are in the same relation because the leads are not displaced by my method of applying the filament.

The end of the filament wire can most conveniently be placed in proper relation to the leads if the wire is held and controlled by a holder such as a wire guide 38, comprising a perforated block through which the wire is threaded and from which the wire projects such a distance that when the holder or guide is set or placed in a convenient location adjacent the leads of the mount, but

far enough away to avoid any displacement of the leads by the guide, the end of the wire will lie across or be in contact with one of the leads, such as lead 31, as indicated in Fig. 4. In order to make sure that the wire will project far enough from the holder or guide 38, I draw the guide or holder back a short distance along the wire after the pinching jaws have closed and pinched the filament wire into the leads and while the jaws are closed as indicated in Fig. 8, so that the pull exerted on the wire as the guide is drawn back is resisted by the pinching jaws. After the guide has been drawn back the wire is cut close to the lead 32, as indicated in Fig. 9, leaving a projecting end long enough to permit the guide 38 to be set far enough away from the leads to avoid any displacement of the leads by it, and yet bring the end of the wire into proper position.

After the proper length of wire has been measured off, shaped if necessary, and secured to the leads, the shaper is removed from between the leads, and the mount is freed from the filament wire by cutting the wire near the lead 32. This wire can be cut with shears, but I prefer to separate it by means of an electric cutter 39, which by means of an arc melts or burns the wire in two, as I have found this a very convenient and effective way of cutting tungsten wire.

Although my improved method can be carried out by hand, its commercial advantages are most apparent when it is practiced by means of machinery which performs many or all of the successive operations automatically and with a speed and accuracy not attainable in hand work. The best form of apparatus at present known to me for making mounts by my improved method is that shown in the accompanying drawings, and many of the advantages of my improved method appear in connection with the operation of this apparatus.

In the particular form of machine which I have illustrated as an example of a machine by means of which my improved method may be practiced to advantage, the various parts as shown in Fig. 13, are mounted on a base 40 conveniently made in the form of a heavy table. The driving mechanism is mounted underneath the top of the frame or table and comprises two driving shafts 41 and 42 set at right angles to each other and geared together to operate at the same speed. For imparting an intermittent or step by step movement to a movable carrier for the mounts, the driving shaft 41 carries a cam 43 for moving a pivoted arm 44 which carries a pawl 45 cooperating with a ratchet wheel 46. In the particular machine shown, the arm 44 swings far enough at each revolution of the

cam 43 to carry the pawl over two of the twenty-four teeth of the ratchet wheel so that the ratchet wheel moves one-twelfth of a revolution for each revolution of the cam. The ratchet wheel 46 is secured to the lower end of a vertical shaft 47 which extends through the top of the base 40 and carries on its upper projecting end a horizontally movable carrier such as a rotatable table 48 for carrying each mount through a number of positions in succession and to which an intermittent or step by step movement is imparted by the mechanism just described, all of which is underneath the top of the base 40. By means of a travelling carrier, such as the rotatable table 48, each mount may be brought into operative relation to different mechanisms in succession, which automatically perform different operations on the mount which is held stationary at each position for a short time. In the particular machine illustrated each mount holder stops in twelve different positions during one complete rotation of the table, although a greater or less number of positions can be used.

The two lead wires 31 and 32 are held in place and side by side during the various operations by means of a travelling holder mounted on the table 48. In this machine there are twelve holders near the rim of the horizontal table 48, each holder consisting of a vertical block 49 having a pair of vertical holes 50, each of a size to receive a lead for the mount and to hold it vertical with the upper end projecting a proper distance above the top of the holder, which thus holds the leads parallel and spaced about the proper distance apart during all of the operations of mount making.

The leading-in wires or leads of the mounts may be placed side by side in the holder at position A in various ways, either by hand or automatically. For simplicity, I have shown a machine in which the holder is loaded at position A by the operator, who then, or while the holder is at position B, places a glass ring 51 over the leads so that it rests on the upper end of the holder. This ring is of a size to fit easily over the leads, and of a height which is only a fraction of the length of lead projecting above the holder head. At position C the glass ring comes within range of the burners 52 which melt it down into the bead 33 in which the leads are embedded.

The ends of the leading-in wires are now spaced a definite distance apart, cut to the proper length, and positioned at the proper distance from the axis of the rotatable table 48, by an automatic spacing and cutting mechanism located at position D. This spacing and cutting mechanism as illustrated more in detail in Figs. 15 and 16 comprises

a stationary housing 53 containing two co-operating blades, one a slidable spacing blade 54 provided with two notches 55 for engaging and spacing the ends of the leads, and the other a slidable cutting blade 56 which forms with the spacing blade 54 a shear for cutting the leads. The housing and blades are carried by a standard 57. The blades are provided with pins or rollers 58 which project into two oppositely inclined slots 59 in a sliding double slotted cam 60 which is actuated through a push rod 61 connected to a cam follower 62 driven by a cam 63 on the driving shaft 42. The ends of these slots 59 are parallel for a short distance so that at each end of its stroke the sliding cam 60 has a certain travel which is idle so far as moving the blades is concerned. As the sliding cam 60 rises the rollers 58 are pushed apart, and the blades 54 and 56 are thereby drawn together, and as it descends the rollers are pulled toward each other and the blades are thereby separated. The parts are so timed that while the holder head is stationary at position D the spacing blade 54 advances toward the mount holder until its middle point is between the two leads and the bottoms of the two notches 55 are at a predetermined distance radially from the axis of the table 48, while at the same time the other blade 56 also advances toward the mount holder and first pushes the two leads 31 and 32 to the bottom of the notches 55 thereby spacing them a definite distance apart and also positioning them a definite distance from the axis of rotation of the table 48, after which it continues to advance and shears off that part of the leads which projects above the spacing blade 54.

To make sure that in each position of the table 48 a holder will be in a definite and correct relation to the various mechanisms which operate upon the mount, I provide an indexing and locking mechanism of which one form comprises a housing 64 placed adjacent position D and carrying a sliding locking bolt 65 provided with a tapered end. Twelve V-shaped notches 66 are cut in the rim of the rotatable table 48 between the holders to receive the end of the bolt 65, although only one of the notches is shown in Fig. 13 where a part of a thin sheet metal cover of the table 48 is broken away to show the notch. Any slight inaccuracy in the angular movement of the table is corrected when the wedge-shaped end of the locking bolt enters a V-shaped notch 66 and furthermore the table is firmly locked as long as the locking bolt is firmly seated in the notch. The locking bolt is yieldingly driven into the notches 66 by some spring actuated automatic mechanism such as a spring driven push rod 67 connected to a cam follower 68 which engages the cam 63 to pull down the rod 67 and retract the bolt, and

which is lifted to seat the bolt in the notch 66 by means of a spring 69 which connects the cam follower 62 of the spacing mechanism to the cam follower 68 of the locking mechanism.

The timing of the mechanism is such that the locking bolt enters the V-shaped notch and positions and locks the table prior to the beginning of any operations of the mount 10 and holds the table firmly in place until the operations at each position are completed. In the particular arrangement shown the cam 63 raises the cam follower 62 and thereby stretches the spring 69 which yieldingly 15 seats the locking bolt 65 in the notch 66 during the first part of the upward movement of the push rod 61, while the sliding cam 60 is moving idly and before the spacing and cutting blades 54 and 56 begin to move. The 20 bolt 65 is held firmly seated while those blades are functioning, and until after those blades have returned to their initial position, whereupon the bolt is retracted and the table freed.

As the mount leaves the spacing and cutting mechanism at position D it is ready to have the filament applied to it. The rotation of the table carries it to the filament applying mechanism at position E, where 25 the filament is automatically secured to the ends of the leads, given the proper shape and length, and then cut off from the spool of wire from which the filament is formed. This filament applying mechanism includes 30 a filament wire feeding device for supplying filament wire from a spool, a filament attaching and shaping device for securing the filament to the leads, and simultaneously giving it the proper shape, and a filament wire cutter for cutting the filament wire 35 after the filament has been secured to the leads.

The filament may be secured to the leads in various ways, as by bending the ends of 40 the leads into hooks or in any other suitable way, but I prefer to attach the filament by embedding it in the leads by pinching. The drawn tungsten wire commonly used for filaments is very much harder than the 45 leads, which are usually made of a nickel steel wire coated with copper, so that if the filament wire is placed across a lead and the wire and lead are pressed together with a powerful pressure the filament wire will 50 sink into the metal of the lead and be firmly embedded in it, making a good electrical connection which is mechanically strong.

The sequence of operations and the various steps of my method of fastening the 55 filament to the leads may best be understood by referring to Figs. 2 to 12 inclusive.

The end of the filament wire 30 is so held, as shown in Fig. 2, that as the leads move to position E the forward lead 31 encounters 60 the filament wire and bends it into the

position of Fig. 3, where it is in contact with the lead and extends across it at right angles. The pinching jaws 36 and 37 with the shaping blade 34 between them, now move forward bodily into operating position shown in Fig. 4, where the pinching jaw 36 can be advanced to grip the lead 31 and the overlapping tungsten wire 30 so tightly between the jaw 36 and the comparatively stiff blade 34 that the wire is 70 clamped to the lead and will not be displaced during subsequent operations. The filament wire guide 38 is now moved into the position indicated in Fig. 6 and swings the wire 30 across the path of the other shaping blade 35 which then advances, engaging the filament wire and drawing more filament wire through the guide 38 and off the spool until finally it overlaps the other shaping blade and the filament is S-shaped, 75 as indicated in Fig. 7, with its ends lying transversely across the leads 31 and 32. The shaping blades 34 and 35 hold the filament in shape while the pinching jaw 36 presses the wire into lead 31 and pinching jaw 37 presses lead 32 against the wire and thereby embeds it in the lead. As there is no force exerted during the pinching which is apt to cause displacement of the 80 leads lengthwise of the wire the filaments are all of very uniform length. While the pinching jaws are still closed the filament wire guide 38 is retracted as shown in Fig. 8 to leave a considerable length of wire 85 between the guide and the lead 32. It remains in this position while the pinching jaws open and the shaping blades separate, as shown in Fig. 9, whereupon the cutter 39 cuts the filament wire close to the lead 32, freeing the mount from the rest of the 90 filament wire and leaving a projecting end of the filament wire 30 of such a length that when the guide 38 returns to the position of Figs. 2 and 3 the end of the filament wire will project far enough from the guide 95 100 to overlap the lead 31 as shown in Fig. 3.

The filament applying mechanism, in the particular machine illustrated, is bodily movable toward and away from the table 105 48. In the particular arrangement shown the pinching jaws or pins 36 and 37, normally held separated by springs, are mounted, as best shown in Fig. 17, in bosses 70 on a sliding block 71 which has a supporting member 72 for the shaping blade 34 and 110 is held by a set screw 73. Bell cranks 74 for actuating the pinching jaws are held by a spring 75 in engagement with a sliding cam 76 having cam surfaces 77 and 78 so related that as the sliding cam moves to the right in Fig. 17 the pinching jaw 36 is closed just enough to clamp the wire to the lead 31 before the other jaw is moved. This cam 115 is slidably mounted in a guide way in the block 71 which in turn is slidably mounted, 120 125 130

as best shown in Figs. 18 and 19, to move radially of the table on a standard 79 secured to the base 40. The sliding cam 76 has a lost motion connection to the block 71 through a pin 80 in the block extending into a slot in the cam. There is also a normally rigid but yielding connection between the cam and block through a compression spring 81 between the block and a lug or projection 82 on the sliding cam 76. To actuate both the cam 76 and the block 71 I connect the sliding cam 76 by a pivoted lever 83 to an actuating face cam 84 having a groove shape as shown to impart the desired movements to the sliding cam 76 and the block 71. The spring 81 is normally of the length shown in Fig. 19, and is strong enough to act as a rigid connection between the sliding cam 76 and the sliding block 71 as long as the block is free to move, but will yield and permit the cam to slide on the block if the block is held stationary by some means, such as an adjustable stop 85, which may be mounted on the block in position to engage the standard 79 when the block is in its forward position shown in Fig. 18.

The filament applying mechanism is in the idle position shown in Figs. 9 and 19, while the table 48 is moving. When the table is locked by the locking bolt 65 with a mount at position E, the end of the filament wire 30 extends across one of the leads, as indicated in Fig. 3, and thereupon the filament applying mechanism moves forward into active position because the cam 84 begins to rock the arm 83 and move both the block 71 and sliding cam 76 forward, that is, to the right as Figs. 13 and 19 are drawn. At first the block 71 moves with the cam because the spring 81 is stiff enough to act like a rigid connection as long as the block is free to move. When the block reaches the position shown in Fig. 18, and the mechanism is in active relation to the mount, as indicated in Figs. 4 to 8, the stop 85 strikes the standard 79 and the block stops, with the shaping blade 34 between the leads of the mount. The sliding cam 76 now slides on the block and enters between the ends of the bell cranks 74, this movement being permitted by compression of the spring 81, until the cam surface 77 causes the corresponding bell crank to move pinching pin 36 toward the shaping blade 34 to clamp the end of the tungsten filament wire to the lead 31 as shown in Fig. 5. The cam 76 now remains stationary while the filament wire feeding mechanism is actuated, as hereinafter described, to draw the filament wire into the path of the other shaping blade 35 as shown in Fig. 6, whereupon the other shaping blade 35 is automatically moved into position, as shown in Fig. 7, where it is in place between the leads and overlaps the blade 34. The shaping blade 35 is carried on the lower

end of an arm 86 resiliently jointed near the middle by a spring hinge 87 which permits the lower end, from which the blade 35 is mounted, to be swung to one side. This arm is mounted on a rock shaft 88 actuated by a crank arm 89 controlled by an adjustable stop 90 which limits the travel of the crank arm and thereby of the blade 35. The crank arm is actuated through a rod 91 from a cam 92 mounted on the drive shaft 42 and so timed with relation to the other parts of the mechanism and so shaped as to swing the blade 35 into place while the sliding cam 76 is stationary, and to hold it in place until after the filament is pinched into the leads.

When the shaping blade 35 is in place and the two shaping blades lie side by side and overlapping as shown in Fig. 7, the movement of the sliding cam 76 is resumed, and now the other cam surface 78 causes the other pinching jaw 37 to move, until at the end of the travel of the sliding cam both pinching jaws are fully home, and the filament is firmly embedded in the leads, as indicated in Fig. 8. The pinching jaws and the shaping blades now remain stationary while the filament wire feeding mechanism moves the wire guide back along the wire into position, as indicated in Fig. 8; to leave a projecting end of the proper length when the filament is cut off as indicated in Fig. 9 from the rest of the wire.

The filament feeding mechanism, which is best shown in Figs. 10 to 12, comprises the wire guide 38, which may be a block having in it a hole slightly larger than the wire, and which is mounted on the free lower end of an arm 93 mounted to swing in a vertical plane. The feed of the wire through the guide is controlled by some suitable friction or tension device, such as a spring blade 94 cooperating with a part or end of the arm 93, and preferably having a pad of felt or leather under it in position to press on the wire. This arrangement permits the wire to be drawn through the guide, but holds it in the position in which it is left. The arm 93 is pivoted to swing in a vertical plane and has a bracket 95 with a spindle on which a spool 96 of filament wire can be held by a friction clamp 97 best shown in Fig. 12 to prevent the spool turning too freely. The arm is mounted on an insulating horizontal axle 98 detachably mounted on pivots in a frame 99 and is positioned by an insulating block 100 mounted on the arm and resting against an adjustable stop 101. The arm is bodily movable in a horizontal plane, as the frame 99 is mounted to swing about a vertical pivot 102 set in a standard 103. The arm 93 has a rounded edge which cooperates with an adjustable stationary finger 104 made of fiber or other insulating material and secured to the standard 103. The pivoted frame is swung in a horizontal

plane by a link 105 actuated by a crank 106 on the upper end of a vertical rock shaft mounted in a vertical pillar 107 and rocked by a crank 108 on its lower end through link 5 work 109 from a cam 110 on the drive shaft 42.

The cycle of operation of the filament wire feeding mechanism is as follows: Assume that the wire guide 38 is in the position of Figs. 2 to 5, which may for convenience be called its first position, and in which it holds the filament wire with its projecting end in place to overlap the lead 31. It remains in this position until the end of the 15 filament wire has been clamped between the pinching jaw 36 and one of the leads of the mount as shown in Fig. 5. During the clamping of the filament wire to the lead 20 frame 99, as best shown in Figure 13, is in its first position, where the lower end of the spring hinged arm 86 on which the shaping blade 35 is mounted is held out of the way and in the position shown in Figures 2 to 5 by the projection 111 on the spool 25 brackets 95 carried by the frame 99. After the pinching jaw 36 has clamped the wire 30 and lead 31 to the shaping blade 34 as above described, so as to grip the end of the wire, the frame 99 swings in a clockwise 30 direction into the second position shown in Fig. 11, where the rounded edge of the arm 93 just touches the end of the lifting finger 104. This movement of the frame 99 permits the shaping blade 35 to swing back into 35 the operative position shown in Figs. 6 to 8 because the jointed arm 86 straightens out when the spool bracket swings out of the way, and also stretches the filament wire across the path of the shaping blade 35, as 40 shown in Fig. 6, so that the wire is caught by the shaping blade in its forward movement and laid across the end of the lead 32 which is free from the pinching jaw, so the filament wire is now across the ends of 45 the leads ready to be attached to them.

During the shaping of the filament the frame 99 remains stationary in the second position, while the shaping blade 35 advances into place alongside the other blade 34 as shown in Fig. 7, thereby shaping the filament and at the same time pulling as much wire as required off the spool because the end of the wire is firmly held between the pinching jaw 36 and the shaping 50 blade 34. Both the pinching jaws are then actuated by the forward movement of sliding cam 76 to sink the filament wire into the lead, and, while the jaws are closed, the filament wire feeding mechanism makes the 55 final movement of its cycle during which the arm 93 is tilted and the wire guide 38 is drawn back to the position shown in Figs. 8, 9 and 12, so as to leave a relatively long end of wire projecting from the guide. 60 The filament wire feeding mechanism is

now in its third position but the filament is still a part of the wire on the spool 96. The filament is cut off from the rest of the wire and the finished mount is freed while the filament feeding mechanism is in its third 70 position and after the pinching jaws have moved back out of the way, as indicated in Fig. 9. Any suitable form of cutting device can be used, but the form which I prefer, and which has been used successfully, is an 75 electrical cutter 39 of which certain parts are shown diagrammatically in Fig. 20. As indicated in this figure the cutter consists essentially of two electrodes 112 mounted side by side and separated by insulation 113 which may in practice be a sheet of mica about 1/64 of an inch in thickness. The two electrodes are connected to the terminals of a battery and with the size of tungsten wire ordinarily used, a potential of six volts or less is sufficient to operate the cutter. In the particular machine shown, the cutter 39 is pivoted and carries the two electrodes to which the electrical connections are made by sliding contacts 114. The cutter is actuated at proper intervals to bring the electrodes to the wire through a push rod 115 actuated from a cam on the driving shaft 42. The mechanism is so timed that the cutter swings up to bring the cutting electrodes 95 into contact with the tungsten wire just after the filament wire feeding mechanism has finished its movements and the filament attaching mechanism has moved back out of the way into the position shown in Fig. 19, so that at the time of cutting the wire the parts are in the relative position indicated 100 diagrammatically in Fig. 9. The cutting electrodes swing up into contact with the wire and sufficient current flows from one electrode to the other at the point of contact with the wire to sever the wire and leave the mount free, to be carried along by the 105 table to a point where it can be removed from the holder.

While I have described my method as exemplified in the making of mounts for incandescent lamps, it is applicable to the manufacture of many other articles, such as certain types of fuses, detonators, and similar devices which consist of a definite length of wire supported by two other wires or supports held side by side by a glass bead or similar spacer. Various modifications and changes in the order of the steps of my method may be made without departing from my invention, and I wish it to be understood that my invention includes all changes and modifications within the 110 scope of the appended claims.

What I claim as new and desire to secure by Letters Patent of the United States, is,—
1. The method which comprises holding the end of a long wire immovable in contact with one of two accurately spaced and 115

- positioned leads, moving said wire and the other lead relatively to bring them into contact at an intermediate point on said wire determined by the position of said other lead, securing the wire to both leads at the points of contact, and cutting the wire adjacent said intermediate point. 65
2. The method which comprises clamping one end of a long wire to one of two spaced and positioned leads, moving said wire and the other lead relatively to bring them into contact and thereby include a predetermined length of wire in circuit, securing the wire to both leads at the points of contact, and cutting the wire. 70
3. The method which comprises holding a long wire perpendicularly across and in contact with one of a pair of spaced and positioned leads, producing relative movement of said wire and leads to lay said wire perpendicularly across the other lead, fastening said wire to both leads at the points of contact, and cutting the wire adjacent said other lead. 75
4. The method which comprises holding the end of a long wire in contact with one of a pair of spaced and positioned leads, bending the adjacent portion of the wire into place between said leads to bring it into contact with the other lead, fastening the wire to said leads at the points of contact, and cutting the wire. 80
5. The method which comprises holding the end of a filament wire in contact with one of a pair of spaced and positioned leads, bending the adjacent portion of the wire to bring it into contact with the other lead at a point on the wire a greater distance from the first lead than the distance between the leads, and fastening the wire to both leads at the points of contact. 85
6. The method which comprises holding the end of a filament wire in contact with one of a pair of spaced and positioned leads, bending the adjacent portion of the wire in one direction around one shaping member, and in the reverse direction around another shaping member, and moving said members and leads relatively to each other to bring the other lead into contact with the wire at a point on the wire beyond the second bend and thereby include both bends in circuit between the leads, and fastening the wire to the leads at the points of contact. 90
7. The method which comprises holding the end of a filament wire in contact with one of a pair of spaced and positioned leads, holding a shaping member adjacent one lead with the wire across said member, moving a second shaping member into engagement with the wire and thence into a predetermined position with relation to said first member thereby bending the wire around said members in a reverse curve, bringing the wire into contact with the other lead, and fastening the wire to both leads. 95
8. The method which comprises holding the end of a filament wire in contact with one of a pair of spaced and positioned leads, placing a shaping member between said leads and in contact with an adjacent portion of the wire, moving a second shaping member into place between said leads in a direction to engage the wire and bend it around the first shaping member and thereby reversely curve the wire and bring it into place between the leads and in contact with the other lead, and fastening the wire to the leads. 100
9. The method which comprises holding the end of a filament wire in contact with one of a pair of spaced leads, bending the adjacent portions of the wire while its end is so held to bring it into contact with the other lead with a length of wire in circuit greater than the length of a straight line between the leads, and fastening the wire to the leads at the points of contact. 105
10. The method which comprises holding the end of a filament wire in contact with one of a pair of spaced leads, bending the wire around a shaper which substantially fills the space between the leads and places the wire in contact with the other lead, and gripping the leads and shaper between pinching jaws to exert sufficient pressure along a line joining the two leads to cause the wire to be embedded in the leads. 110
11. The method which comprises placing across a pair of leads a wire bent into a reverse curve which fills the space between the leads and causes the wire to lie across the other lead, supporting the bent wire to prevent closing up of the bends, and exerting upon the leads and wire in a direction tending to close said bends a pressure sufficient to embed the wire in the leads at the points of contact. 115
12. The method which comprises placing the end of a long wire across one lead of a pair of spaced and positioned leads, clamping it to said lead to hold it against displacement, bending the adjacent portion of the wire into a reverse curve which fills the space between the leads and causes the wire to lie across the other lead, fastening both said leads to the wire at the points of contact, and cutting the wire adjacent the other lead. 120
13. The method which comprises placing the end of a wire across one lead of a pair of spaced leads, clamping it to said lead to hold it against displacement, bending the adjacent portion of the wire into a reverse curve which fills the space between the leads and causes the wire to lie across the other lead, and embedding the wire in the leads at the points of contact. 125

14. The method which comprises placing the end of a long wire across one lead of a pair of spaced and positioned leads, clamping it to said lead to hold it against dis-
5 placement, bending the adjacent portion of the wire into a reverse curve which fills the space between the leads and causes the wire to come into contact with the other lead with a predetermined length of filament wire in
10 circuit, and supporting the bent wire to prevent closing up of the bends, embedding the wire in said leads at the points of contact by pressure exerted in a direction tending to close said bends, and cutting the wire ad-
15 jacent one of said leads.
15. The method which comprises spacing the ends of a pair of lead wires a predetermined distance apart, clamping the end of a long filament wire to one of said lead wires near the end thereof, bending the adjacent portion of the filament wire to insert it between said leads and bring it into contact with the other lead at a point dependent upon the spacing of the leads, mechanically and electrically connecting said filament wire to said leads at the points of contact, and cutting said filament wire adjacent one of said leads.

In witness whereof, I have hereunto set my hand this 23d day of November, 1921.

WILLIAM R. BURROWS.
